(57) **CLAIM**

The ornamental design for a flexible beverage pouch with fitment and contoured waist, as shown and described.

DESCRIPTION

FIG. 1 is a front elevational view of my new design illustrating the characteristic features of the design which resides in its shape together with having an opaque upper portion, transparent middle portion, and opaque lower portion on both the front and back of the pouch, the rear elevational view being identical;

FIG. 2 is a left side elevational view of the design illustrated in FIG. 1, the right side elevational view being identical;

FIG. 3 is a bottom view thereof; and,

FIG. 4 is a top view thereof.
